UNITED STATES PATENT OFFICE.

HENRY J. NEUFANG, OF ATLANTA, NEW YORK.

REVERSIBLE PLOW.

Application filed November 13, 1924. Serial No. 749,755.

To all whom it may concern:

Be it known that I, HENRY J. NEUFANG, a citizen of the United States, residing at Atlanta, in the county of Steuben and State of New York, have invented certain new and useful Improvements in Reversible Plows, of which the following is a specification.

My invention relates to an improvement in reversible plows.

It has for its primary object facility in turning the plows over at the end of the furrow, in order to make it possible to plow back along the same furrow, without plowing around the land as is necessary with the old-fashioned mold-board plow.

There are two main features in this present invention, one of which includes simple means for reversing the plows from the front of the machine, and the second is the means for turning and adjusting the caster-wheel located at the rear, also from the front of the machine, so that both means for the adjustment of the machine are easily reached and manipulated from a common point at the front of the machine.

In the accompanying drawings:—

Fig. 1 is a side elevation of my improved plows;

Fig. 2 is a fragmentary view in longitudinal section;

Fig. 3 is a similar plan view;

Fig. 4 is a section on line 4—4 of Fig. 3 looking in the direction of the arrow;

Fig. 5 is a view of the wishbone bracket on the end of the adjustable sleeve which carries the plows and colters or jointers; and

Fig. 6 is a bottom plan view of the pivoted segment on the caster-wheel spindle.

The numeral 1 represents a tubular bar constituting the central framework of the machine. This is supported at the forward end on wheels 2 made vertically adjustable by the hand-lever 3, and the caster-wheel 4 at the rear.

A sleeve 5 is mounted and capable of being turned or axially adjusted upon the central tubular bar 1.

The plows 6 and the colters or jointers 7 are secured to this sleeve in any approved manner, as, for instance, by the fastening means 8. A wish-bone bracket 9 is secured by bolts 10 to the forward end of the sleeve 5. A trip-bar 11 is rotatably supported in bearings 12 located on the frame of the ma-

chine, its rear end being bent to one side as shown in Figs. 1, 2 and 3, and extended into the wishbone bracket 9, for engaging one side or the other of the bracket 9 to throw the plows over from one position (say that shown in Fig. 1) to the reverse.

This trip-bar 11 may be locked by any approved means. As a simple method, the toothed segment 13 is keyed upon the forward end of the tripping bars 11, and the teeth of this segment mesh with the teeth of the pinion 14 on the shaft 15. Shaft 15 turns in bearings 16 on the frame of the machine, and has a crank 17 at the forward end thereof which the operator manipulates when he desires to reverse the plows. Means is provided for locking the sleeve 5, which carries the plows and colters, in its extreme position. This is provided for by means of a slide-bolt 18 actuated in one direction by a spring 19, and holes 20 are provided in the collar 21 on the sleeve at opposite points to receive this bolt 18 as shown in Fig. 2. Stop-shoulders 22, one on either side, limit the movement of the sleeve in each direction. The spring-actuated slide-bolt 18 is operated by the hand-lever 23 through the rods 24 and 25 and lever 26 as a simple means for pulling the bolt out of engagement with the hole 20 in the collar 21.

It is sometimes desirable to adjust the position of the caster-wheel at the rear of the machine, and especially on hilly soil to counteract the tendency of the plow to work downwardly away from the land in plowing. This adjustment is accomplished through the medium of a shaft 27 extending through the tubular bar 1, as viewed in Figs. 2 and 4. This has a bevel pinion 28 on the rear end which engages the teeth of the fan-shaped segment 29, which segment is held on the spindle 30 of the caster-wheel by a set-screw or other means 31, as viewed in Figs. 1, 2, 3 and 6.

On the forward end of the machine, the crank 32 is provided as a convenient means for turning the shaft 27. A toothed wheel 33 is secured on the shaft adjacent to the crank, and a pivoted latch 34 is employed as a means for locking it in its adjusted position. Thus all means of adjustment are brought to a common point within easy reach of the operator, making it easy to shift or reverse the plows and adjust the caster-wheel.

I claim:

1. In a reversible plow the combination of a tubular bar, a sleeve rotatably mounted thereon, and a shaft rotatable within the tubular bar, plows carried by the sleeve, a caster-wheel for the support of the rear end of the tubular bar, and separate and independent means located at the forward end of the plow for reversing the plows and for 10 steering the caster-wheel through the medium of the shaft.
2. In a plow the combination of a tubular bar, earth working means carried thereby, adjustable wheels for the support of the forward end of said bar, and a caster wheel supporting the rear end, a shaft extending through the tubular bar and having a crank on one end, by which it is turned, and means at the other end for transmitting 15 motion to the spindle of the caster-wheel for steering the latter.
3. In a plow the combination of a tubular bar, earth working means carried thereby, adjustable wheels for the support of the forward end of said bar, and a caster wheel supporting the rear end, a shaft extending through the tubular bar and having a crank on one end, by which it is turned, means at the other end for transmitting motion to the 20 spindle of the caster-wheel for steering the latter, and means for locking the shaft.
4. In a plow the combination of a tubular bar, earth working means carried thereby, a shaft extending through said tubular bar and rotatable therein, and having a bevel pinion at the rear end and means for turning said shaft at the forward end, a caster-wheel having a spindle which has a toothed segment engaged by the pinion, and means 25 connected with the shaft and the tubular bar for locking the latter.
5. In a reversible plow the combination of a bar, wheels for supporting the latter, a sleeve rotatably mounted upon the bar, and

adapted to carry two sets of plows thereon, 45 a wishbone bracket secured to the forward end of said sleeve, a rotatably supported trip-bar having an end extending into the wishbone bracket as a means for shifting the bracket and reversing the plows, means for turning the trip-bar, means for limiting the rotation of the sleeve, and means for locking the sleeve.

6. In a reversible plow the combination of a bar, wheels for supporting the latter, a sleeve rotatably mounted on the bar, earth working means carried by said sleeve, a wishbone bracket secured to the sleeve, a rotatable trip-bar, one end of which extends into the wishbone bracket, a pinion on the 55 opposite end, a toothed segment keyed on the bar, a shaft having a pinion engaging the teeth of the segment, a spring-actuated slide-bolt for locking the sleeve, and means for limiting the movements of the sleeve. 65

7. In a reversible plow the combination of a tubular bar, wheels for supporting the latter, a sleeve rotatably mounted on the bar, plows carried by said sleeve, a wishbone bracket secured to the sleeve, a rotatable trip-bar, one end of which extends into the 70 wishbone bracket, a pinion on the opposite end, a toothed segment keyed on the bar, a shaft having a pinion engaging the teeth of the segment, a spring-actuated slide-bolt for locking the sleeve, means for limiting the movements of the sleeve, a shaft rotatably supported within the tubular bar, and having a crank on one end for operating the same, and a beveled pinion on the 75 opposite end, toothed segments secured to the spindle of the rear wheel, the teeth of which are engaged by the beveled pinion, and means for locking said shaft in any position to which it is turned. 85

In testimony whereof I affix my signature.

HENRY J. NEUFANG.
